UNITED STATES PATENT OFFICE.

GEORGE H. NATZEL AND FRANK E. JACKSON, OF SANTA ANA, CALIFORNIA.

DESIGN FOR A BUILDING.

Application filed March 14, 1928. Serial No. 25,854. Term of patent 14 years.

To all whom it may concern:

Be it known that we, GEORGE H. NATZEL and FRANK E. JACKSON, citizens of the United States of America, both residing at Santa Ana, in the county of Orange and State of California, have invented a new, original, and ornamental Design for Buildings, of which the following is a specification, reference being had to the accompanying drawings, forming a part thereof.

Figure 1 is a view in side elevation of the building.

Figure 2 is a plan view thereof.

Figure 3 is a view in side elevation of the upper portion of the building.

Figure 4 is a transverse section taken on line 4—4 of Figure 3.

We claim:

The ornamental design for a building as shown.

GEORGE H. NATZEL.
FRANK E. JACKSON.
